[57] **ABSTRACT**

A break prevention device for a calendar watch wherein the calendar advancing wheel includes an elongated adjusting tooth formed with a partial slope at its end and resiliently displaceable out of the plane of the calendar wheel.

5 Claims, 3 Drawing Figures

PATENTED JUN 27 1972

3,672,156

FIG. 1

FIG. 2

FIG. 3

**BREAK PREVENTION DEVICE FOR CALENDAR
ADVANCING OF A CALENDAR WATCH**

BACKGROUND OF THE INVENTION

This invention relates to a break prevention device for calendar advancing of a calendar watch.

In a conventional calendar watch having a quick day or date correcting device, for the several hours during which a calendar wheel is rotated by a calendar gear train, an edge of the calendar advancing tooth and the like obstructs the free rotation of the calendar wheel and the calendar cannot be corrected quickly. If the user applies a strong force to the mechanism without knowing these facts, the calendar advancing device, the calendar correcting device, the calendar gear train, and the minute wheel gear train may be broken. Therefore, in order to prevent this, it is necessary to use an intricate mechanism associated with the finger for calendar advancing.

SUMMARY OF THE INVENTION

A break prevention device for a calendar watch is provided including a calendar advancing wheel having an elongated adjusting tooth formed with a partial slope at its end and resiliently displaceable out of the plane of the calendar wheel when said slope is engaged by a calendar wheel tooth.

The object of this invention is to provide a break prevention device for a calendar advancing finger which is simple and effective without increasing the number of parts in the watch.

Still other objects and advantages of the invention will in part be obvious and will in part be apparent from the specification.

The invention accordingly comprises the features of construction, combination of elements, and arrangement of parts which will be exemplified in the constructions hereinafter set forth, and the scope of the invention will be indicated in the claims.

BRIEF DESCRIPTION OF THE DRAWING

For a fuller understanding of the invention, reference is had to the following description taken in connection with the accompanying drawing, in which:

FIG. 1 is a plan view of an embodiment of the present invention;

FIG. 2 is a partial perspective view of said embodiment; and

FIG. 3 is a cross sectional view of FIG. 2 and explains the operation of said embodiment.

DESCRIPTION OF THE PREFERRED EMBODIMENTS

In FIG. 1, a date advancing wheel 1 is equipped with a date advancing tooth 3 which is made longer than the other teeth in order to advance a date wheel 2. Date advancing wheel 1 is rotated one complete revolution each day by a transmitting wheel 5 mounted on an hour wheel. The end of the date advancing tooth 3 has a partial slope 4 at its end as shown in FIG. 2, said date advancing tooth having elasticity, so that it can be bent up and down. A hole 6 in the plate is provided in the region between date wheel 2 and date advancing wheel 1 so that the date advancing tooth can be bent downwardly. A date correcting wheel 7 is placed so as to correct the date wheel, said date correcting wheel being rotated through a crown in a manner not shown.

In the arrangement according to the invention as described

above, date correcting may be effected by the correcting wheel 7 even while date advancing tooth 3 advances the date wheel 2. In such circumstances, as shown in FIG. 3, date advancing tooth 3 is pushed downwards along slope 4 by the teeth of date wheel 2 and moved into hole 6 of the plate. Accordingly, breakage on account of date correction is avoided. In addition, in the arrangement according to the invention, when the date advancing wheel is in a position to advance the date wheel 2, said date advancing wheel may be reciprocated in its position to advance the teeth of the date wheel one by one. In this manner, date correcting may be easily performed in watches having no date correcting mechanism.

As described above, unlike conventional constructions which require special date advancing teeth and the like, break prevention and date correction by reciprocal displacement of the date advancing wheel are obtained without increasing the number of parts and the size of the watch. Further, the arrangement according to the invention has many advantages in respect of manufacturing, cost and use. In addition this construction is usable in the other advancing mechanisms such as the month advancing or day advancing mechanisms.

It will thus be seen that the objects set forth above, and those made apparent from the preceding description, are efficiently attained and, since certain changes may be made in the above constructions without departing from the spirit and scope of the invention, it is intended that all matter contained in the above description or shown in the accompanying drawing shall be interpreted as illustrative and not in a limiting sense.

30 It is also to be understood that the following claims are intended to cover all of the generic and specific features of the invention herein described, and all statements of the scope of the invention which, as a matter of language, might be said to fall therebetween.

35 What is claimed is:

1. A break prevention device for a calendar watch comprising a rotatable calendar wheel having a plurality of teeth; and a calendar advancing wheel having at least one elongated advancing tooth positioned for cooperative engagement with said calendar wheel teeth for the incremental advancing of said calendar wheel in response to the rotation of said calendar advancing wheel in a first direction, said advancing tooth being formed with a sloped region adjacent its end and being resiliently displaceable out of the plane of said calendar wheel teeth, whereby said advancing tooth drives said calendar wheel when rotated in a first direction, while permitting said calendar wheel to rotate in a second direction opposed to said first direction.

2. A break prevention device as recited in claim 1, wherein 50 said watch includes a plate supporting at least one of said calendar advancing wheel and said calendar wheel, said plate being formed with an aperture therethrough in the region facing the point of contact between said advancing tooth and said calendar wheel teeth for permitting said resilient displacement of said advancing tooth.

3. A break prevention device as recited in claim 1, when 55 said calendar wheel is a date wheel.

4. A break prevention device as recited in claim 1, wherein 60 said calendar wheel is a day wheel.

5. A break prevention device as recited in claim 1, wherein 65 said calendar wheel is a month wheel.
